UNITED STATES PATENT OFFICE.

CLARENCE P. CHAMBERLIN AND CHESTER T. FEZZEY, OF DETROIT, MICHIGAN.

DOUBLE ENVELOP.

1,141,688.

Specification of Letters Patent. Patented June 1, 1915.

Application filed November 11, 1914. Serial No. 871,453.

To all whom it may concern:

Be it known that we, CLARENCE P. CHAMBERLIN and CHESTER T. FEZZEY, citizens of the United States, residing at Detroit, county 5 of Wayne, State of Michigan, have invented a certain new and useful Improvement in Double Envelops, and declare the following to be a full, clear, and exact description of the same, such as will enable others skilled 10 in the art to which it pertains to make and use the same, reference being had to the accompanying drawings, which form a part of this specification.

This invention relates to envelops for 15 mailing purposes and its object is a double compartment envelop for the joint mailing of first class and lower class mail matter.

Heretofore in mailing catalogues or other matter requiring less than first class postage, 20 it has been necessary to mail such matter separately from a letter referring thereto causing much inconvenience as frequently the matter to which the letter pertains is not received until a considerably later time than 25 the letter. With the double envelop here shown, the letter accompanies the lower class matter and both are received at the same time.

A further object of the invention is an inexpensive envelop for the purpose which 30 may be formed from a single piece of material.

These objects and the various novel features of construction are hereinafter more 35 fully described and claimed and shown in the accompanying drawings in which—

Figure 1 is a perspective view of the envelop ready for mailing. Fig. 2 is a similar view showing both compartments open. 40 Fig. 3 shows the blank from which the envelop is formed.

Similar characters refer to similar parts throughout the drawings and specification.

The envelop is formed of two separate 45 compartments, the compartment 1 being preferably of comparatively large size to receive catalogues, samples, or other lower class mail matter, while the compartment 2 is to be used for first class mail matter and 50 is practically of the size of an ordinary letter-size envelop. It is to be understood however that both compartments may be made of any size desired without departing from the spirit of this invention. The compartment 2 is provided with a gummed flap 3 by means of which it may be sealed and

when sealed the compartment 2 may be folded down over the opening of the compartment 1 providing a closure therefor.

The compartment 1 is preferably provided 60 with a double tongued clasp 4 adapted to be inserted through an aperture 5 formed near the outer edge of the compartment 2 when the envelop is folded and the clasp tongues are then bent over in the usual manner indicated in Fig. 1. This brings the reverse side 65 of the compartment 2 to wait on which is to be placed the address and first class postage, as indicated in Fig. 1. The reverse side of the compartment 1 is also adaptable for 70 use in addressing on which side is also to be placed the postage for the lower class matter.

Both compartments are formed from a single blank of the general form shown in Fig. 3. The part 10 of the blank is first 75 folded on the dotted line 11 and is glued to the back of the blank substantially on the dotted line 12. The flap 13 is then folded over the end of the part 10 and the opposite end is provided with the gummed flap 3 80 heretofore mentioned, by means of which the compartment 2 may be sealed. The lower side flap 14 is next folded over on the body of the blank along the dotted line 15. The similar lower side flap 16 is then folded 85 along the dotted line 17 and glued to the first side flap 14, as is indicated in Figs. 1 and 2. The lower end flap 18 is then folded over and glued or secured to the bottom ends of the flaps 14 and 16 providing a compartment 90 having an open end as indicated at 19 in Fig. 2.

With an envelop thus formed, catalogues and other samples may be readily inserted in the compartment 1 and a letter relative 95 thereto may be inserted in the compartment 2 and which is then sealed with the gummed flap 3. The compartment 2 is then folded downward over the mouth of the compartment 1 providing a closure therefor that may 100 be held in place with the clasp 4 after the manner now in use with envelops for lower class mail matter.

Having thus briefly described our invention, its utility and mode of construction, 105 what we claim and desire to secure by Letters Patent of the United States is—

1. A blank for forming a double compartment envelop comprising a main body portion having two comparatively large side 110 flaps less in length than the said body and adapted to be folded thereover, one of said

- flaps being gummed to secure the flaps in folded relation, and a gummed end flap adapted to be folded over and secured to the ends of the said side flaps; said body portion 5 having additional comparatively small gummed side flaps adjacent the first mentioned side flaps and extending approximately half the remaining length of the body portion, the remaining part of the said 10 body portion being gummed at the end and adapted to be folded upon itself and secured in place, the two small gummed side flaps being adapted to be folded over the said folded body portion and secured thereto.
- 15 2. A double compartment envelop composed of a blank formed of a single piece of material having a main body portion provided with opposite side flaps less in length than the said body and adapted to be folded 20 thereover, one of said flaps being gummed for attachment to the other to secure the flaps in folded relation, a gummed end flap adapted to be folded over and secured to the ends of the said side flaps; said body 25 portion having additional gummed side flaps parallel with the first mentioned side flaps and the adjacent end of the body portion being gummed and being adapted to be folded upon itself and secured in place, said 30 additional gummed side flaps being adapted to be folded over the ends of said folded body portion and secured thereto.
3. A double compartment envelop com-
- posed of a blank formed of a single piece of material having a body portion provided 35 with two comparatively large side flaps greater in length than half the length of the body portion and adapted to be folded thereover, one of said flaps being gummed and attachable to the other to secure the flaps in folded relation, a gummed end flap adapted to be folded over and secured to the ends of the said side flaps, the compartment thus formed being open at the opposite end, a 40 clasp secured to the overlapped portion of said side flaps; said body portion of the blank having additional comparatively small gummed side flaps adjacent the first mentioned side flaps and extending approximately 45 half the remaining length of the body portion, the body portion being gummed at the end and adapted to be folded upon itself and secured in place, the folded body portion having an aperture at the folded end to receive the clasp when the 50 compartments are in folded relation, the two small gummed side flaps being adapted to be folded over the folded body portion and secured thereto.
- 55

In testimony whereof, we sign this specification in the presence of two witnesses.

CLARENCE P. CHAMBERLIN.

CHESTER T. FEZZEY.
